UNITED STATES PATENT OFFICE.

JAMES WILLIAM WHITMORE, OF RICHMOND, VIRGINIA, ASSIGNOR OF ONE-
FOURTH TO JAMES W. WHITMORE, JR., OF SAME PLACE.

HINGE.

SPECIFICATION forming part of Letters Patent No. 333,375, dated December 29, 1885.
Application filed August 18, 1885. Serial No. 174,747. (Model.)

To all whom it may concern:

Be it known that I, JAMES W. WHITMORE, of Richmond, in the county of Henrico and State of Virginia, have invented new and useful Improvements in Hinges, of which the following is a full, clear, and exact description.

This invention relates to hinges suitable for doors and gates of different kinds; and it consists in a hinge of novel construction, whereby it and the door or gate attached to it may be made self-closing or not, as desired, substantially as hereinafter shown and described.

Reference is to be had to the accompanying drawings, forming part of this specification, in which similar letters of reference indicate corresponding parts in all the figures.

Figure 1 represents a horizontal partly sectional view of a hinge embodying my invention, with the parts in position for producing a self-closing action of the hinge and showing the hinge as closed. Fig. 2 is a further longitudinal partly sectional view of the hinge under a like adjustment of its parts, but showing it opened; and Figs. 3 and 4, are similar views to Figs. 1 and 2 of the hinge, but showing its parts as adjusted to make it not self-closing.

A indicates the one half-section or leaf of the hinge, which is designed to be secured on the door or gate, and A' the other half-section or leaf of the hinge to be attached to the frame which carries the door or gate.

B is the socket portion of the leaf A, arranged to extend above the upper edge of said leaf, and having a screw-thread, b, on the exterior of its upper end, and square or angular chamber or aperture, c, in and through its upper end in direction of the length of the socket. The screw-threaded end b of the socket B serves to receive over and to engage with it a screw-cap, C, by which the adjustment is made to convert the hinge into a self-closing or non-closing one, as desired. Fitted to slide up and down within the angular chamber c is a correspondingly-shaped coupling, D, having a shank, d, which passes up through or within the screw-cap C, and admits of the screw-cap turning about or around it, but by means of a pin or screw, e, entering within an annular groove, f, in the shank, insuring the coupling D rising and falling with the screw-cap.

B' is the socket portion of the other leaf, A', of the hinge constructed to enter up and turn within the lower end of the other socket B, and provided with an upwardly-projecting fast hinge-pin, E, on which is a screw-thread, g, 55 that engages with an elongated nut, G, which is free to turn and rise and fall within a chamber, h, in the upper end of the socket B'. The upper end of this nut G is constructed to engage by an angular shank, i, with an angular 60 socket, j, in the lower end of the coupling D, so as when engaged to turn with said coupling, but permitting of its disengagement from the coupling.

Accordingly as the screw-cap G is turned to 65 the right or to the left, when the hinge is secured by its leaves A A' to the door or gate and its frame, will the hinge and the door or gate be made self-closing or not, as desired. These adjustments of the screw-cap are only 70 made when the hinge is closed. Thus, supposing the hinge to be closed, as shown in Fig. 1, and the screw-cap C to be screwed down, as there shown, then the coupling D will be caused to engage with the nut G, and on opening the 75 door or gate the leaf A of the hinge and door or gate attached thereto will be raised one-fourth of an inch, more or less, by the unscrewing of the nut G on the screw g of the pin E, as shown in Fig. 2. Thus, if the hinge 80 be applied to the door of an apartment, it will enable the door to clear the carpet, and on releasing hold of the door it and its attached leaf part A of the hinge will be made self-closing by their own weight, through the working 85 down of the nut G on the thread g of the pin E, again bringing the upper and lower edges of the leaves A A' into line with one another, as shown in Fig. 1. By unscrewing or raising the cap C, as shown in Fig. 3, when the hinge 90 and door or gate are closed, then the coupling-pin D will be disengaged from the nut G, and the hinge, when opened, as shown in Fig. 4, or closed, as shown in Fig. 3, will operate as an ordinary hinge, and its leaf A, with its attached door or gate, will not rise in opening or fall in closing. This adaptability of the hinge from a self-closing to a non-closing one, and vice versa, will be found exceedingly convenient, and any unskilled hand, or even a 95 100

child, may do it by simply and suitably turning, as described, the cap C when the door or gate is closed. When adjusted to make the hinge a self-closing one, the action is a positive screw-thread and nut one within the socket portion of the hinge, and the construction is a permanent and durable one, requiring no spring, and the working portions of the hinge will be protected from exposure to rain or weather liable to injure them; also, the screw-thread b is or may be concealed by constructing the lower end of the screw-head or cap C with an extended socket, as shown.

Having thus described my invention, I claim
15 as new and desire to secure by Letters Patent—
In hinges for doors and gates, the half-sec-

tions or leaves of the hinge, having sockets the one of which is fitted to turn and slide up and down the other, in combination with a screw in the interior of the one socket, a nut fitting 20 said screw, and a coupling capable of manipulation from the exterior applied to the other socket, and adapted to engage and disengage with and from the nut, whereby the hinge may either be a self-closing one or be converted into 25 a hinge which is not capable of self-closing, substantially as specified.

JAMES WILLIAM WHITMORE.

Witnesses:

P. HELSTERN,
JOHN J. TYLER.

It is hereby certified that Letters Patent No. 333,375, granted December 29, 1885, upon the application of James William Whitmore, was erroneously issued to the said Whitmore and "James William Whitmore, Jr."; that said Letters Patent should have been issued to *James William Whitmore, James William Whitmore, Jr., Jed. H. Bascom, and Thomas P. Kilgore* as assignees; and that the said Letters Patent should be read with this correction therein that the same may conform to the record of the case in the Patent Office.

Signed, countersigned, and sealed this 19th day of January, A. D. 1886.
